Primary Examiner — Robert M Spear*Assistant Examiner* — Ryan Harvey(74) *Attorney, Agent, or Firm* — Laurence A. Greenberg;
Werner H. Stemmer; Ralph E. Locher(57) **CLAIM**

The ornamental design for a hand grip, as shown and described.

DESCRIPTION

FIG. 1 is a rear perspective view of a hand grip;

FIG. 2 is a front elevation view thereof;

FIG. 3 is a rear elevation view thereof;

FIG. 4 is a left side elevation view thereof; the right side view being a mirror image thereof;

FIG. 5 is a top plan view thereof; and,

FIG. 6 is a bottom plan view thereof.

The broken lines shown represent unclaimed subject matter and form no part of the claimed design.
